CLAIM

The ornamental design for a display screen with virtual three-dimensional shoe icon or display system with virtual three-dimensional shoe icon as shown and described.

DESCRIPTION

FIG. 1 is a front view of a display screen with virtual three-dimensional shoe icon in which the icon is shown in a front bottom perspective orientation;

FIG. 2 is another front view thereof, showing a bottom orientation thereof;

FIG. 3 is another front view thereof, showing a rear bottom perspective orientation thereof;

FIG. 4 is a front view of a display system with virtual three-dimensional shoe icon shown in a side view, the virtual three-dimensional shoe icon being the same design as shown in FIGS. 1-3;

FIG. 5 is another front view thereof, showing a bottom orientation thereof; and,

FIG. 6 is another front view thereof, showing a rear bottom perspective orientation thereof.

The broken line showing of the lightning bolt-shaped region forms no part of the claimed design. The uneven-length broken lines depicting the remainder of the shoe icon form no part of the claimed design. In FIGS. 1-3, the outermost even-length broken line represents a display screen which forms no part of the claimed design. In FIGS. 4-6, the outermost even-length broken line represents a portion of a field of view for a visual display and forms no part of the claimed design.

The icon in FIGS. 1-6 is shown in various orientations to provide an understanding of the three-dimensional appearance of the design.
